(57) **CLAIM**

The ornamental design for an automotive tissue valet, as shown and described.

DESCRIPTION

FIG. 1 is a three-dimensional isometric view of a first embodiment of an automotive tissue valet;

FIG. 2 is a top plan view thereof;

FIG. 3 is a three-dimensional isometric view of a second embodiment of an automotive tissue valet; and,

FIG. 4 is a top plan view thereof.

The dash-dash broken lines along the strap and strap receiver shown in FIGS. 1 and 3 is for the purpose of depicting stitching and forms no part of the claimed design. The dot-dash broken lines depict the boundaries of the automotive tissue valet, and form no part of the claimed design.

1 Claim, 4 Drawing Sheets
